ATTACHMENT FOR LINE CASTING MACHINES

Leonard C. Geissel, South Pasadena, Calif.

Application February 2, 1939, Serial No. 254,172

11 Claims. (Cl. 199—61)

My invention relates to an attachment for typesetting machines such as Linotype, Intertype and the like.

An important object of the invention is to provide means to feed brass rule, leads, slugs, pre-set lines and other line-length elements used in the printing art, into the composing stick on such line casting machines.

Another object is to provide a key controlled means for feeding line-length elements into the composing stick of a line casting machine, between lines formed by the machine.

Still another object is to provide safety means which will automatically release an actuating lever in case the operation of the attachment is interfered with.

The invention also comprises novel details of construction and novel combinations and arrangements of parts, which will more fully appear in the course of the following description.

In the drawings, like reference characters designate similar parts in the several views.

Figure 1 is a broken front elevation showing an embodiment of my invention attached to adjacent parts of such a typesetting machine.

Figure 2 is an enlarged bottom view looking in the direction of the arrow A of Figure 1.

Figure 3 is a bottom view similar to Figure 2 but showing the parts in a different operative position.

Figure 4 is an enlarged vertical section taken on the line 4—4 of Figure 1.

Figure 5 is a broken section taken on the line 5—5 of Figure 4.

Figure 6 is a section taken on the line 6—6 of Figure 2.

Figure 7 is a broken detail of means to remove elements from a magazine, as more fully described hereinafter.

The numeral 8 indicates a broken view of a vise frame of a Linotype, Intertype or the like. A locking bolt is shown at 9 provided with a handle 10 for tightening the vise frame in position opposite the molten metal pot (not shown).

Slidably mounted on the vise frame 8 is an elevator 12. Thus far is conventional construction.

Bolted to the elevator 12 is a cam 13.

The attachment includes a magazine 14 for rules, leads, slugs, or pre-set lines. A lug 15 is fastened upon the magazine 14 by means of legs 16 and 17. Bolt 18 fastens the lug and thereby the attachment in place at the side of the elevator 12. It will be noticed in Figure 2 that the lug 15 has an inclined shoulder 19 along which

the elevator 12 reciprocates. A bolted lug 20, opposite the lug 15, similarly controls the opposite edge of the elevator 12.

Converging slides 21 and 22 together form a chute that receives line-length elements from the magazine 14 and directs such elements into the composing stick (not shown) of the machine.

An arm 23 on the lug 15 provides a shaft 29 upon which a lever 24 oscillates. The lever 24 comprises arms 25 and 26. A bearing 27 on the lever 24 provides means for the oscillation of such lever. The arm 25 of the lever is disposed in the path of the cam 13.

An auxiliary arm 28 is also mounted to swing on the shaft 29. Movement of the arm 26 is communicated to the arm 28 by means of a relatively stiff spring 30 which has legs 31 and 32 that are bent around both the arms 26 and 28. This spring tends to cause the arms to follow each other's movements unless the arm 28 strikes a substantially immovable obstruction, in either direction. In such event, the arm 26 may swing relative to the arm 28.

Another spring 33 is also mounted on the shaft 29. This latter spring has one end fastened to a collar 34 on the arm 23 and the other end 35 of the spring 33 is hooked around the arm 25. By this arrangement the spring 33 tends to return the lever 24 to the position shown in Figure 2.

A reciprocating selector 36 reciprocates in oppositely grooved slides 37. The selector 36 has a notched face as best shown at 38 in Figure 7. This notched face 38 receives the printing edge of the rule 39 or other line-length element in the magazine 14.

A coil spring 40 on a pin 41 adjustably supports the selector 36 with regard to the bottom of the magazine 14. The selector plate 36 is hooked through a reciprocating bar 42, upon which bar the spring 40 and pin 41 are mounted by means of a yoke 43. A plate 44 on the yoke 43 is apertured, as shown at 45, for receiving a reduced end 46 of the arm 28. A stop 47 limits movement of the plate 44 to the right in Figure 6. The spring 33 tends to move the plate 44, through the intermediary of the arm portion 46, against the stop 47.

Mounted at either side above the slides 21 and 22 is a pair of rods 48. Slidably on these rods 50 between stops 49 and 50 is a flanged plate 51, one of whose flanges 52 is opposite a relatively stationary flange 53 above the slides 21, 22. A helical spring 54 tends to move the plate 51 to a position in which a rule, lead, slug or pre-set 55

line 39 is supported on the flanges 52, 53 above the slides 21, 22.

To withdraw the plate 51 and its flange 52, a lever 55 is provided with a key 56 readily accessible to the operator. The lever 55 is fulcrumed at 57 on a lug 58 on the magazine. One end of a bar 59 is pivoted at 60 on the lever 55. The other end of the bar 59 is fastened to an ear 61 on the plate 51.

10 A hook 62 on the plate 51 has an inclined cam face 63 which is engaged by a pin 64 on the bar 42. When the pin 64 has caught under the hook 62, as shown in Figure 3, the reciprocating bar 42 is held in the position shown in the latter figure until the operator releases the plate 51 by means of tapping the key 56. Tapping the key 56 not only releases the reciprocating bar 42 so that spring 33 may return to its original position, but also withdraws the flange 52 allowing the element to drop down the chute provided by the slides 21, 22.

In the operation of my present device, a supply of rules, leads, slugs or other line-length elements are inserted into the magazine 14 and rest 25 on the top of the grooved slides 37.

When the elevator 12 descends, the cam 13 engages the lever arm 25 thus tripping the lever 24. Movement of the lever arm 26 carries with it the arm 28, which in turn reciprocates the selector 36, which pushes the bottom element from the stack in the magazine over until said element rests on the flanges 52 and 53 above the slide elements 21, 22. As soon as the selector has moved the bottom element over on the flanges 52, 35 53, the pin 64 on the reciprocating bar 42 is caught under the hook 62. This maintains the lever 24 in a tripped position until the element that is resting on the flanges 52, 53 is released. This combination of elements prevents the cam 40 13 from tripping the lever 24, as long as there is an element on the flanges 52, 53.

When the operator wishes one of the elements to be fed from the present attachment, he depresses the key 56, which moves the plate 51 to 45 the left in Figure 5, thus drawing the flange 52 out from under the element 39, which causes the element 39 to drop down the chute and into the composing stick. As soon as the plate 51 withdraws its associated hook 62, the spring 33 moves 50 the lever 24 back to the position shown in Figure 2, so that it is ready to be tripped upon the next descent of the elevator 12.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, 60 but desire to avail myself of all modifications which may fall within the scope of the appended claims.

Having thus described my invention, what I claim and desire to secure by Letters Patent is:

65 1. An attachment for a line casting machine having a composing stick, comprising a magazine for a supply of pre-formed line-length elements, a chute at the side of the magazine for feeding the elements into the composing stick, means to move the bottom element from the magazine to the chute, means to maintain the element at the chute, and key-controlled mechanism operable independently of the line casting means of 75 the machine, to manually release the latter

means, to drop the element down the chute into the composing stick.

2. An attachment for a typesetting machine having a composing stick and having a part that moves each time a line is set, comprising a magazine for a supply of pre-formed line-length elements, lever means to move automatically the bottom element from the magazine to a position ready to be fed to the composing stick, the lever being arranged in the path of the moving part 10 on the typesetting machine, to be tripped by being engaged by said part, spring-urged locking means to maintain the lever in the tripped position until manually released, and manually controllable means to release the lever and feed the 15 separated element into the composing stick.

3. An attachment for a typesetting machine having a composing stick and having a cam that moves each time a line is set, comprising a magazine for a supply of pre-formed line-length elements, a chute at the side of the magazine for feeding the elements into the composing stick, lever means to move automatically the bottom element from the magazine to a position ready 20 to be fed to the composing stick, the lever being arranged in the path of the cam, to be tripped by being engaged by the cam, spring-urged locking means to maintain the lever in the tripped position until manually released, and manually controllable means to release the lever and feed the 25 separated element into the composing stick.

4. An attachment for a typesetting machine having a composing stick and having a part that moves each time a line is set, comprising a magazine for a supply of pre-formed line-length elements, a reciprocating selector to move the bottom element from the magazine to a position ready 35 to be fed to the composing stick, a pin associated with the selector, a lever arranged to be engaged and tripped by the moving part on 40 the typesetting machine, the lever being connected with the selector to effect said actuation of the bottom element by the selector when the lever is tripped, spring means tending to resist the tripping movement of the lever and to return 45 same to its inoperative position when released, a spring-urged catch to engage said pin and maintain the selector in its said actuating position and the lever in its said tripped position until manually released, and manually controllable 50 means to release the lever and feed the separated element into the composing stick.

5. An attachment for a typesetting machine having a composing stick, comprising a magazine for a supply of pre-formed line-length elements, means to move the bottom element from the magazine to a separated position in which it is ready to be fed into the composing stick, spring-urged means tending to support said element in said separated position until released 60 manually, and a key-controlled mechanism to manually release the latter means, against the action of the spring, and allow the element to drop into the composing stick.

6. An attachment for a typesetting machine 65 having a composing stick and having a part that moves each time a line is set, comprising a magazine for a supply of pre-formed line-length elements, a reciprocating selector to move the bottom element from the magazine to a position 70 ready to be fed to the composing stick, spring means to vary the position of the selector with regard to the bottom of the magazine, a lever arranged to be engaged and tripped by the moving part on the typesetting machine, the lever 75

being connected with the selector to effect said actuation of the bottom element by the selector when the lever is tripped, spring-urged locking means to maintain the lever in the tripped position until manually released, and manually controllable means to release the lever and feed the separated element into the composing stick.

7. An attachment for a typesetting machine having a composing stick and having a part that moves each time a line is set, comprising a magazine for a supply of pre-formed line-length elements, a reciprocating selector having a notched face to engage the bottom element in the magazine at either side of its printing face and thereby 10 to move the element from the magazine to a position to be fed to the composing stick, a lever arranged to be engaged and tripped by the moving part on the typesetting machine, the lever being connected with the selector to effect said actuation of the bottom element by the selector 15 when the lever is tripped, spring-urged locking means to maintain the lever in the tripped position until manually released, and manually controllable means to release the lever and feed the separated element into the composing stick.

8. An attachment for a typesetting machine having a composing stick and having a part that moves each time a line is set, comprising a magazine for a supply of pre-formed line-length elements, a reciprocating selector to move the bottom element from the magazine to a position ready to be fed to the composing stick, a lever arranged to be engaged and tripped by the moving part on the typesetting machine, a swinging arm connected with the selector to effect said actuation of the bottom element by the selector, spring means connecting the lever with the arm and arranged to effect conjunctive movement of the lever and arm during tripping movement of the lever, whereby the lever may be tripped independently of the arm if the arm or subsequently operated mechanism is out of order, spring-urged locking means to maintain the lever and the arm in the tripped position until manually released, and manually controllable means 40 to release the lever and the arm and feed the separated element into the composing stick.

9. An attachment for a typesetting machine having a composing stick and having a part that moves each time a line is set, comprising a magazine for a supply of pre-formed line-length elements, a reciprocating selector to move the bot-

tom element from the magazine to a position ready to be fed to the composing stick, a swinging arm connected with the selector to effect said actuation of the bottom element by the selector, a lever arranged to be engaged and tripped by the moving part on the typesetting machine, spring means tending to resist the tripping movement of the lever and to return same to its inoperative position when released, spring means connecting the lever with the arm and arranged 10 to effect conjunctive movement of the lever and arm during return movement of the lever to its inoperative position, whereby the lever may return to its inoperative position independently of the arm if the arm or associated parts are out of order, spring-urged locking means to maintain the lever and the arm in the tripped position until manually released, and manually controllable means to release the lever and the arm and feed the separated element into the composing stick. 15

10. In a typesetting machine having a magazine of matrices, metal casting means to cast a line of type from a series of such matrices and a composing stick for receiving such lines, a separate magazine for a supply of elements, and manually controllable means connected to individually separate elements from the supply in the latter magazine and direct said elements from the latter magazine directly to the composing 20 stick, said means being operable apart from any operation of the casting means.

11. In a line casting machine having a magazine of matrices, metal casting mechanism, means to assemble a line of the matrices below said mechanism, an elevator movable from a lower stationary position to an upper stationary position to receive the line of matrices from said means and to raise the line to said mechanism to cast a line from the matrices, and a composing 25 stick for receiving successively cast lines: a separate magazine for a supply of elements, and manually controllable means connected to individually separate at will elements from the supply in the latter magazine while the elevator 30 is in a stationary position, the operation of the latter means being apart from the operation of any other part of the machine, and the latter means directing said elements from the latter magazine directly to the composing stick. 35

LEONARD C. GEISSEL.
